GEORGE SCHWIBINGER, OF MILWAUKEE, WISCONSIN, ASSIGNOR TO RUNDLE-SPENCE MANUFACTURING COMPANY, OF MILWAUKEE, WISCONSIN, A CORPORATION OF WISCONSIN.

AUTOMATIC FLUSHING MECHANISM FOR CLOSETS.

1,157,186.

Specification of Letters Patent.

Patented Oct. 19, 1915.

Application filed July 2, 1910. Serial No. 570,040.

To all whom it may concern:

Be it known that I, GEORGE SCHWIBINGER, a citizen of the United States, residing at Milwaukee, county of Milwaukee, and State 5 of Wisconsin, have invented new and useful Improvements in Automatic Flushing Mechanism for Closets, of which the following is a specification.

My invention relates to improvements in 10 automatic flushing mechanism for closets, and it pertains more especially to that class by which the flushing valves receive their initial action from the closet seat.

My invention is further explained by reference to the accompanying drawings, in which—

Figure 1 represents a side view of a closet and an elevated water tank provided with my improved automatic flushing mechanism. Fig. 2 is a vertical section of the tank, showing a side view of the valve mechanism therein. Fig. 3 is a vertical section of said flushing tank, showing a front view of the flushing mechanism therein, and 25 Fig. 4 is a detail, part in vertical section, of the device for communicating motion from the closet seat to the valve operating mechanism, whereby the latter is set preparatory to automatically actuating the discharge valve as soon as pressure is withdrawn from the seat.

Like parts are identified by the same reference numerals throughout the several views.

It will be understood that the closet bowl 1, the water tank 2, the water duct 3, leading from the tank to the bowl, the inlet water duct 4, valve mechanism 5, float 6, water discharge duct 7, lever 8, and the 35 mechanism for communicating motion from the float 6 to the lever 8, are all substantially of the ordinary construction and need not be herein more specifically described. It will also be understood that the siphon duct 40 9, which communicates from the bottom of the tank with the upper end of the duct 3 is also of ordinary construction and invention is predicated herein more especially upon the mechanism for automatically communicating motion from the seat to the valve mechanism by which the water is caused to flow from the tank to the closet. 45 50 55

10 represents the seat of the closet, which is rigidly connected with the operating lever

11 and said operating lever 11 is connected 55 with the closet through the bracket 12 and pivotal bolt 13. The lever 11 is also pivotally connected with the vertically moving rod 14, through the bracket 15 and pivotal bolt 16, and the upper end of the rod 14 is 60 rigidly affixed to the sliding member 16' by a threaded bearing 17 and said member 16' is slidably supported from the tank within a sleeve 18.

19 is a collar, which is rigidly affixed to 65 the rod 14.

20 is a spiral spring, which is interposed 70 between the upper side of the collar 19 and the lower side of the sleeve 18, whereby as the rod 14 is raised by the downward pressure upon the seat, said spring will be compressed, and whereby as soon as the pressure upon the seat is removed, said rod 14 will be forced down by the recoil of said 75 spring.

Motion is communicated from the 80 slideable member, 16' to the flushing valve, 26, through the swinging member 21, lever 25, and links 28 and 29. The member 21 is pivotally supported from said slideable member 85 16', upon the bolt 22. The member 21 is provided with a rearwardly extending lug 21' which is adapted to bear against the right hand side of the sleeve 18, reference being had to Fig. 2 of the drawings, whereby said member 21 is prevented from swinging 90 toward the left as it is moved downwardly in contact with the short arm 24 of the lever 25.

It will now be understood that when 95 downward pressure is applied to the seat, an upward movement will be communicated to the member 21 through the intermediate mechanism described, whereby the lower end 23 of the member 21 is raised and caused to swing of its own gravity above the short arm 24 of the lever 25, whereby as soon as downward pressure upon the seat is relieved, the lever 21 will be brought into contact with the end of the short arm 24 of 100 said lever. Said short arm will be forced down by the re-coil of said spring 20, acting through the intermediate parts named, and the flushing valve 26 will be quickly raised, when the water will escape from the tank 105 through the outlet duct 3 to the closet.

Novelty in the present invention consists primarily in the mechanism by which the

swinging member 21 is brought into position to actuate the valve 26 as soon as downward pressure is applied to the seat. It will be understood that the rod 14 and sliding member 16' are moved upwardly by downward pressure on the seat and that the swinging member 21 is pivotally suspended from the upper left hand corner of said sliding member, and that as soon as said swinging member 21 passes the upper end of said short arm 24, it will swing to the left of its own gravity, whereby it is brought above the end of the short arm 24 of said lever preparatory to actuating the same after the pressure on the seat has been removed. When the pressure on the seat has been removed, said swinging member 21 will be forced downwardly by the recoil of the spiral spring 20, whereby the short arm 24 of said lever is moved downwardly and the valve 26 which is connected with the long arm of said lever will be raised. As the member 21 is thus moved downwardly against the short arm 24 of said lever, the lower end of said member 21 will simultaneously swing toward the right until it escapes past the short arm of said lever, when the valve 26 is therefore retained in its raised position by the catch 30 engaging beneath the stop 31 independently of the action of said swinging member 21.

It will be understood that when the swinging member 21 is brought above the short arm 24 of the lever, it will force said short arm down whereby the valve 26 will be raised, motion being communicated from the short arm 24 to said valve 26 through the long arm 27 of said lever and links 28 and 29, said link 29 being connected at its lower end to said valve 26 and said valve will be retained in its raised position until the water escapes from the tank to the closet. The valve 26 is thus retained in its raised position by the sliding catch 30, which as the valve is raised, engages beneath the angular stop 31, said stop 31 being rigidly secured to said link 29.

It will be understood that as the long arm 27 of the lever 25 is being raised, the short arm 24 is simultaneously moved outwardly by its sliding contact with the swinging member 23 until it escapes past the lower surface of said swinging member, when said parts will be again brought back to the position shown in Fig. 2 of the drawing.

Thus it is obvious that the valve having been raised until the stop 31 engages beneath the catch 30, it will be retained in its raised position until said catch 30 is withdrawn from beneath the stop 31 and the catch 30 is withdrawn from beneath the stop 31 by the gravity of the float 32, as soon as the water escapes from the tank. The float 32 is connected with the catch 30

through the lever 33, bracket 34 and pivotal bolt 35. It will be understood that so long as the water remains in the tank, the float 32 will be buoyed up and retained in its buoyed position, whereby the catch 30 will remain beneath the stop 31 and the valve 26 will remain open, as stated, until the contents of the tank have been discharged. When, however, the contents are discharged, said catch 30 will be withdrawn from the stop, thus permitting said valve 26 to close, when it will remain in its closed position until the operation previously described is again repeated. When the valve 26 has been raised, as described, and the current of water once started in the discharge duct 8, said discharge will be supplemented by the passage of water through the siphon duct 9 in the ordinary manner.

The upper end of the rod 14 and the spiral spring 20 are preferably surrounded by an inclosing sleeve 37, which sleeve serves the additional purpose of a guide for the spring supporting collar 19. The upper end of the rod 14 has slidable bearings in the aperture 38 of the sleeve 18, whereby said rod and said member 16' are free to be moved upwardly and downwardly as pressure is applied to and removed from the seat 10.

The member 21 is preferably made in the shape of an inverted T, and the same is pivoted at its upper end to the slidable member 16', while the lower end is adapted as said slidable member 16' is raised to swing of its own gravity above the short arm 24 of the lever 25, whereby as soon as said slidable member 16' is released from the upper pressure of the user it is moved down by the recoil of the spiral spring 20, whereby the lower end 23 of the member 21 is caused to press downwardly upon the short arm 24 of the lever 25, whereby said valve 26 is raised from its seat when water is free to pass from the tank 2 to the closet.

It will be understood that the swinging member 21 is brought above the lever of the short arm 24 of the valve operating lever by its own gravity, preparatory to raising the valve 26 after the pressure on the seat has been removed, but that no action whatever, is communicated to the valve or its operating mechanism by such downward pressure upon the seat. The member 21 is simply brought into position to act after the pressure on the seat has been removed. When, however, the pressure on the seat is removed, the swinging member 21, as it is being drawn down by the re-coil of the spiral spring 20, will contact with the short arm 24 of the lever, and thereby cause the valve 26 to be raised from its seat, but when said valve 26 has been raised from its seat, the member 21 will have passed out of contact with the end of the lever 24; and ceased

to act thereon, when the valve 26 will be retained in its raised position, as stated, by the float actuated catch, 30, engaging beneath the stop 31, until the water has escaped from the tank, and said latch, 30, is withdrawn from the stop 31 by the gravity of the float.

Having thus described my invention, what I claim as new, and desire to secure by Letters Patent, is—

In a device of the described class, a water closet, a water tank located above said closet, a duct leading from said tank to said closet and a valve for closing said duct, in combination with the mechanism herein described for automatically opening said valve, consisting in the combination of a two armed lever for raising said valve, the arms of which lever are of unequal lengths, a swinging member pivotally supported above the short arm of said lever a vertically sliding member upon which said swinging arm is mounted a sleeve inclosing

said sliding member, a rearwardly extending lug formed in connection with said swinging member and adapted to bear against one side of the inclosing sleeve of said vertical sliding member, the long arm of said lever being connected with said valve, a seat pivotally connected with said closet, means for communicating motion from said seat to and for raising said swinging member as a downward pressure is communicated to said seat, a spring for forcing said swinging member down upon the short arm of said lever as the downward pressure upon said seat is removed, whereby said valve is raised and the contents of said tank is discharged into said closet.

In testimony whereof I affix my signature in the presence of two witnesses.

GEORGE SCHWIBINGER.
